[57] CLAIM

The ornamental design for a decanter, substantially as shown and described.

DESCRIPTION

FIG. 1 is a front elevational view of a decanter showing my new design;

FIG. 2 is a side elevational view of the decanter shown on FIG. 1;

FIG. 3 is a rear elevational view of the decanter shown on FIG. 1;

FIG. 4 is a top plan view of the decanter shown on FIG. 1; and

FIG. 5 is a bottom plan view of the decanter shown on FIG. 1.

The side opposite that shown in FIG. 2 is a mirror image of the side shown.
